Primary Examiner — Barbara Fox*Assistant Examiner* — Kristin E Reed(74) *Attorney, Agent, or Firm* — Lawrence G. Fridman, Esq.; Feigin & Fridman, LLC(57) **CLAIM**

The ornamental design for a shovel adapter, as shown and described.

DESCRIPTION

FIG. 1 is a right side view of a shovel adapter, showing my new design;

FIG. 2 is a top plan view thereof;

FIG. 3 is a left side view thereof;

FIG. 4 is a bottom plan view thereof;

FIG. 5 is a front elevational plan view thereof;

FIG. 6 is a rear elevational view thereof;

FIG. 7 is a perspective view thereof;

FIG. 8 is a side elevational view thereof in a folded position; and,

FIG. 9 is a rear elevational view thereof.

The broken lines are for the purpose of illustrating an environmental structure and form no part of the claimed design.

1 Claim, 5 Drawing Sheets(56)
